US00D349861S

United States Patent [19]

Kanewske et al.

[11] **Patent Number:** Des. 349,861[45] **Date of Patent:** ** Aug. 23, 1994[54] **AUTOMATED ANALYTICAL INSTRUMENT**

[75] Inventors: **William J. Kanewske**, Dallas, Tex.; **Max K. Yoshimoto**, San Mateo; **Brett C. Lovelady**, San Jose, both of Calif.

[73] Assignee: **Abbott Laboratories**, Abbott Park, Ill.

[**] Term: **14 Years**

[21] Appl. No.: **915,169**

[22] Filed: **Jul. 20, 1992**

[52] U.S. Cl. **D10/81**

[58] Field of Search 422/50-68.1, 422/72; 436/43-45, 55; 364/509, 497; 356/440; 73/431; 222/23, 25, 30; D10/46, 75, 81; D24/185, 186, 232, 234, 216

[57]

CLAIM

The ornamental design for an automated analytical instrument, as shown and described.

DESCRIPTION

FIG. 1 is a perspective view of an automated analytical instrument, showing our new design;

FIG. 2 is a front elevational view of the automated analytical instrument shown in FIG. 1;

FIG. 3 is a top plan view of the automated analytical instrument shown in FIG. 1;

FIG. 4 is a rear view of the automated analytical instrument shown in FIG. 1;

FIG. 5 is a left-side elevational view of the automated analytical instrument shown in FIG. 1; and,

FIG. 6 is a right-side elevational view of the automated analytical instrument shown in FIG. 1.
